(57) **CLAIM**

The ornamental design for a shoe heel resembling a smoking article, as shown and described.

DESCRIPTION

FIG. 1 is a perspective view of a shoe heel resembling a smoking article, shown attached to a shoe.

FIG. 2 is a perspective view thereof, shown attached to a shoe.

FIG. 3 is a right side elevational view thereof, shown attached to a shoe.

FIG. 4 is a left side elevational view thereof, shown attached to a shoe.

FIG. 5 is a back elevational view thereof, shown attached to a shoe.

FIG. 6 is a bottom plan elevational view thereof, shown attached to a shoe.

FIG. 7 is a perspective view of the shoe heel resembling a smoking article.

FIG. 8 is a perspective view showing the portion of the shoe heel resembling a smoking article indicated by the box 8 in FIG. 7.

FIG. 9 is a top plan view thereof of the shoe heel resembling a smoking article.

FIG. 10 is a bottom plan view thereof.

FIG. 11 is a front elevational view thereof.

FIG. 12 is a cutaway side elevational view thereof, taken along the lines 12-12 in FIG. 9 through the transparent material excluding the smoking article; and,

FIG. 13 is a perspective view of FIG. 12 in an alternate position.

The broken lines in the drawing depict environment and form no part of the claim.

The dash-dot broken lines appearing in FIGS. 7 and 8 depict the cut lines in FIG. 7 for the enlarged view of FIG. 8.

1 Claim, 11 Drawing Sheets
